DESIGN FOR A CIGARETTE VENDING CABINET

Lloyd Rose, Long Beach, N. Y.

Application March 1, 1939, Serial No. 83,278

Term of patent 7 years

To all whom it may concern:

Be it known that I, Lloyd Rose, a citizen of the United States and resident of Long Beach, in the county of Nassau and State of New York, have invented a new, original, and ornamental Design for Cigarette Vending Cabinets, of which the following is a specification, reference being had to the accompanying drawing, forming a part thereof.

Fig. 1 is a front elevational view of a cigarette vending cabinet, showing the same in closed position.

Fig. 2 is a rear elevational view of the same.

Fig. 3 is a side elevational view of the same.

Fig. 4 is a front perspective view showing the same in open position.

I claim:

The ornamental design for a cigarette vending cabinet, as shown.

LLOYD ROSE.
